UNITED STATES PATENT OFFICE.

ELIJAH T. GASKILL, OF NEWBERN, NORTH CAROLINA, ASSIGNOR OF ONE-THIRD TO
CALEB D. BRADHAM AND ONE-THIRD TO THOMAS D. WARREN, BOTH OF NEWBERN,
NORTH CAROLINA.

PACKAGE-TIE.

1,181,868.

Specification of Letters Patent.

Patented May 2, 1916.

Application filed July 29, 1915. Serial No. 42,585.

To all whom it may concern:

Be it known that I, ELIJAH T. GASKILL, a citizen of the United States, residing at Newbern, in the county of Craven and State 5 of North Carolina, have invented certain new and useful Improvements in Package-Ties; and I do declare the following to be a full, clear, and exact description of the invention, such as will enable other skilled 10 in the art to which it appertains to make and use the same.

This invention relates to new and useful improvements in package ties, and more particularly to the provision in a merchantable form, of a device of the above mentioned class, which may be easily and simply applied to packages, and more particularly letters and the like, and is especially applicable for use in post offices.

20 A further object of the invention is to provide a device of this character which is simple and durable in construction, inexpensive to manufacture, and one which will be very efficient in operation.

25 With these and numerous other objects in view, my invention consists of the novel features of construction, combination and arrangement of parts which will be herein referred to and more particularly pointed 30 out in the specification and claim.

In the accompanying drawings: Figure 1 is a top plan view of my improved package tie showing its application to use; Fig. 2 is a side elevation of the same; Fig. 3 is a 35 detail perspective view of the tie.

In describing my invention, I shall refer to the drawings in which similar reference characters designate corresponding parts throughout the several views and in which 40 the numeral 1 designates my improved package tie which consists of an elongated flat strip of metal of uniform width throughout its entire length, and having an aperture 2 therein adjacent one end and 45 which is adapted to be attached or connected to the end of a fastening cord 3. The other end of this strip is bent transversely upward at right angles to the plane of the metal strip, in the form of an S, to form 50 inner and outer cord receiving and guiding channels 4 and 5 for a purpose to be hereinafter more fully described. It will be noted that this S-shaped upwardly bent end of the metal strip is merely adapted 55 to form two cord receiving and guiding

channels, and will not grip the cord held therein in any manner, but merely forms a stop or support therefor.

A bent integral centrally disposed longitudinally extending cord attaching clip or 60 spring tongue 6 is struck up from the metal strip, and the said clip or tongue 6 is curved arcuately adjacent its connected end as shown at 7, to form a cord engaging portion for the same, and the extremities of 65 said clip or tongue which is disposed above the horizontal plane of the strip has formed thereon a projecting lip 8 which is inclined upwardly therefrom and is adapted to act as a guide to direct the end of the cord 70 under the clip to engage the same. This clip or tongue 6 is adapted to form a resilient integral connecting means to hold the opposite end of the cord when the same is engaged with the package to be held by the 75 said tie as clearly shown in Fig. 3 of the drawing.

In the operation, when it is desired to fasten the package, for instance a bundle of letters, firmly and securely together, the 80 metal strip 1 is placed on top of the package, and longitudinally positioned with respect thereto, and the end of the said strip to which the cord is attached is positioned adjacent one of the ends of the package as 85 shown in Fig. 1 of the drawings. The cord 3 is then wrapped longitudinally around the package of letters, and then transversely across the same and therearound, being held in the said transversely extending position 90 by means of the inner and outer cord receiving or engaging channels 4 and 5 of the S-shaped upwardly bent end of the strip. The end of the cord 3 that projects from the outer cord receiving channel 5 on the said 95 S-shaped end of the strip is then moved forwardly, until it engages the projecting lip 8 of the clip or tongue of the strip. The cord is then moved or pulled rearwardly whereby the same will be guided by the 100 lip beneath the clip and will be firmly and securely held with respect thereto. When in this position which is clearly shown in Figs. 1 and 2, the letters will be firmly and 105 securely held together by this tie, and when it is desired to detach the letters, it is merely necessary to disengage the end of the cord 3 from the clip or tongue 6 and to unwrap the same to accomplish this purpose. This package tie is especially adapted 110

for use in post offices where it is desired to wrap the smaller packages and bundles of letters together, as this device affords an easy and simple manner of so wrapping said letters, and also when the tie is removed from the letters, it may be easily placed in an accessible position, on the wall for instance, so that the same may be ready for use again when desired.

From the foregoing description of the construction of my improved package tie, the manner of applying the same to use and the operation thereof will be readily understood and it will be seen that I have provided a simple, inexpensive and efficient means for carrying out the objects of this invention.

I claim:

A package tie comprising a flat metal strip of uniform width having an aperture in one end to attach a cord thereto, the other end of said strip being bent inwardly substan-

tially upon itself and then outwardly, in the shape of an S positioned at right angles to the horizontal plane of the strip to form 25 opposed inner and outer cord receiving and guiding channels, a centrally disposed bent cord attaching spring clip struck up from the strip and having its connected end positioned adjacent the bent S-shaped end of 30 said strip, and its free end terminating a short distance above the same, and a guide lip on said free end of the spring clip inclined upwardly therefrom to direct the cord beneath the said free end so that the 35 cord can be readily inserted under and held by the spring clip.

In testimony whereof I have hereunto set my hand in presence of two subscribing witnesses.

ELIJAH T. GASKILL.
